E. L. JOHNSON

2,491,465

HIGH CHAIR

Filed April 21, 1945

UNITED STATES PATENT OFFICE

2,491,465

HIGH CHAIR

Everard L. Johnson, Patchogue, N. Y.

Application April 21, 1945, Serial No. 589,536

4 Claims. (Cl. 155—127)

1

This invention relates to high chairs or infants' chairs. More particularly, the invention deals with a means for swingably and slidably supporting the tray or table portion of a chair in connection with the arms to move the tray or table portion out of the path of access to the seat in placing a child in or removing the child from the chair. Still more particularly, the invention deals with means for adjustably clamping the tray or table member in one of a number of positions on the arms, adapting the tray or table to closely fit a child and aiding and retaining a child against accidental displacement from the chair, while also keeping food supported on the tray in close proximity to a child.

The novel features of the invention will be best understood from the following description when taken together with the accompanying drawing, in which certain embodiments of the invention are disclosed and, in which, the separate parts are designated by suitable reference characters in each of the views and in which:

Fig. 1 is a perspective view of a high chair made according to the invention with part of the construction broken away and showing the tray or table in operative position in full lines and in inoperative position in dot and dash lines.

Fig. 2 is a sectional detailed view of one side portion of the chair, as seen in Fig. 1, with parts of the construction broken away and in section.

Fig. 3 is a front view of a chair showing part of the construction in section and showing a modification.

Fig. 4 is a bottom plan view of part of the structure, as seen in Fig. 3.

Fig. 5 is a side view of a bracket portion, shown in Figs. 3 and 4.

Fig. 6 is a section on the line 6—6 of Fig. 5; and Fig. 7 is a section on the line 7—7 of Fig. 4.

In high chair constructions, it has been the general practice to support a tray or table by rearwardly extending arms pivoted at the rear portion of the chair or the back-rest thereof to swing vertically over the head of a child in the operation of placing a child in or removing a child from the chair.

It is the purpose of my invention to so mount a tray or table member as to facilitate downward swinging of the same, as well as to provide means for adjustably clamping the tray or table in one

2

of a number of positions in the chair to bring the tray or table into a desirable position with respect to a child positioned in the chair and to establish a reasonably close proximity to the child to prevent accidental displacement of the child from the chair.

In Figs. 1 and 2 of the drawing, I have shown one adaptation of my invention and, in Fig. 1, 10 represents a high chair which may be of any design and construction and will employ the conventional seat 11, back-rest 12, supporting legs 13, foot-rest or treadle 14, arms 15 extending forwardly from the back-rest 12 and suitably supported at their forward ends by members 16.

15 In the present construction, the outer surfaces of the arms, particularly at their forward end portions, are provided with longitudinal slots, channels or grooves 17, in which operates the lower flange 18 of channel plates 19 secured to the lower surface of a tray or table 20 adjacent the side portions thereof. This construction provides free adjustment of the tray or table into different positions longitudinally of the arms 15 while, at the same time, permitting the tray or table 20 to be detached from the forward ends of the arms to swing downwardly into the position indicated in dot and dash lines in Fig. 1, this operation being accomplished through side supporting and clamping links 21. The links 21

20 are in the form of rather substantial rods, to one end 22 of which are pivoted two brackets 23 secured to the lower surfaces of the tray or table at inner side corner portions thereof, as clearly seen in Fig. 1 of the drawing. The other ends 25 of the links or rods 21 are provided with enlargements or ball ends 24 which retain the same against displacement from clamp brackets 25 secured to outer edges of the seat 10 adjacent the forward corner portions thereof, as clearly seen in Fig. 1.

30 The brackets 25 comprising outwardly extending round-bearing portions 26 having heads providing swivel mountings 27 in the plates 28 of said brackets; the swivel mountings 27 are in the form of inwardly tapered heads. The bearings 26 are apertured, as seen at 29, to receive the links or rods 21. The bearings 26 also support clamp screws 30 having milled or roughened heads 31. It will be understood that, when the screws 30 are loosened, the rods 21 are free to

slide through the bearings 26 and these bearings are free to swing in the plates 28 in moving the tray from the position shown in full position in Fig. 1 to the dotted line position of said figure or in adjusting the tray 20 to different positions on the arms 15. In tightening the screws 30, the tray will be supported in any position of adjustment.

In Figs. 3-7 inclusive, I have shown another form of construction. In Fig. 3, 32 represents a tray or table similar to 20, 33 arms similar to the arms 15, 34 channel couplings, similar to the couplings 19. In this figure, 35 represents the forward portion of the seat which is shown in section; 36 represents rods similar to the rods 21; 37 are pivot brackets similar to the brackets 23.

Instead of providing the clamp screw construction shown in Figs. 1 and 2, I provide in Figs. 3-7 inclusive clamp elements 38 which are slidably supported in spaced bearings or keepers 39 formed from an elongated metal strip 40 secured to the lower face of the seat 35 and extending to the side edges of the seat as will clearly appear from a consideration of Fig. 3.

The strip 40 also has a pivot 41 secured centrally thereof on which is mounted a lock lever 42, the pivot end portion of which is provided with two cam surfaces 43 adapted to operate upon inner spaced ends of the elements 38, as clearly illustrated in Fig. 4 of the drawing. The lever has at its outer end a fingerpiece 44 facilitating operation thereof and this end of the lever has an angularly extending corrugated finger 45 adapted to operatively engage one of the rods 38, as clearly seen in Figs. 4 and 7 of the drawing, to retain the lever in a predetermined locking position, when the rods 38 have been forced outwardly into firm engagement with the links or rods 36 retaining the latter against shifting movement in the supporting bearings 46 therefor. One of the bearings 46 is shown in sectional detail in Fig. 6 of the drawing and has a portion 47 extending into a supporting bracket 48 and retained against displacement therefrom by a nut or collar 49 while, at the same time, providing rotary movement of the bearing 46 in the bracket. Each bracket 48 is secured to the outer side edge of the chair and the bracket is of an offset construction, so as to extend the portion 47 of the bearing 46 to a position to receive the element 38 operating from the lower surface of the chair seat.

It will be understood that, when the lock lever 42 is swung outwardly from the position shown in Fig. 4, the cams 43 will free the inner ends of the elements 38, thus releasing all pressure on the rods 36 permitting said rods 36 to swing and slide freely in shifting the position of the tray or table 32 or in swinging the same into a lowered position in the manner of swinging the tray 20 as in Fig. 1.

One advantage of the construction shown in Figs. 3-7 inclusive is that the lock or control element constitutes a single member and is at a position out of any possible reach by a child and, in a single operation, both rods 36 are locked against movement, whereas in Figs. 1 and 2, each element 31 must be operated to lock or loosen the rods 21.

Having fully described my invention, what I claim as new and desire to secure by Letters Patent is:

1. A high chair comprising a seat, a back rest secured thereto and side arms connected with the back rest and seat, said arms having longitudinal

grooves opening through the front ends of said arms, a tray having flanged members slidably engaging the grooves of said arms to permit adjustment of the position of the tray thereon and displacement of the tray from said arms, means comprising fixed pivots on the rear side portions of the tray and front side portions of the seat for adjustably retaining the tray in different positions of adjustment on said arms and for swinging the tray outwardly and downwardly when displaced from said arms, said last named means comprising rods having sliding movements in the pivots at the sides of the seat, means for retaining the rods against sliding movement in said last named pivots, said last named means comprising an element adapted to engage each rod, and a common manually operated member for moving said elements into operative engagement with said rods.

2. A high chair comprising a seat, a back rest secured thereto and side arms connected with the back rest and seat, said arms having longitudinal grooves opening through the front ends of said arms, a tray having flanged members slidably engaging the grooves of said arms to permit adjustment of the position of the tray thereon and displacement of the tray from said arms, means comprising fixed pivots on the rear side portions of the tray and front side portions of the seat for adjustably retaining the tray in different positions of adjustment on said arms and for swinging the tray outwardly and downwardly when displaced from said arms, said last named means comprising rods having sliding movements in the pivots at the sides of the seat, means for retaining the rods against sliding movement in said last named pivots, said last named means comprising an element adapted to engage each rod, a common manually operated member for moving said elements into operative engagement with said rods, said member having a pair of cam surfaces operatively engaging said elements, and means on said member cooperating with one element for retaining said member in locked position.

3. In a high chair having a seat and arms supported above said seat, a tray slidably supported upon said arms, rods pivotally supported to rear side portions of the tray, pivots fixed at front side portions of the seat, said pivots having rotatable parts, said rods slidably engaging the rotatable parts of said pivots, an elongated supporting strip secured to the lower surface of the front portion of the seat, elements slidably engaging said strip, said elements having spaced adjacent ends and outer ends adapted to engage said rods at said pivots, and means movably supported on the strip operatively engaging spaced adjacent ends of said elements for moving said elements into operative engagement with said rods in retaining the tray in different positions of adjustment on said arms.

4. In a high chair having a seat and arms supported above said seat, a tray slidably supported upon said arms, rods pivotally supported to rear side portions of the tray, pivots fixed at front side portions of the seat, said pivots having rotatable parts, said rods slidably engaging the rotatable parts of said pivots, an elongated supporting strip secured to the lower surface of the front portion of the seat, elements slidably engaging said strip, said elements having spaced adjacent ends and outer ends adapted to engage said rods at said pivots, means movably supported on the strip operatively engaging

spaced adjacent ends of said elements for moving said elements into operative engagement with said rods in retaining the tray in different positions of adjustment on said arms, said last named means comprising a manually operated lever, cam surfaces on said lever engaging said spaced adjacent ends of said elements, and means on the lever engaging one of the elements to retain said lever in operative position.
